UNITED STATES PATENT OFFICE.

FREDERICK J. EMPSON, OF SYDNEY, NEW SOUTH WALES, AUSTRALIA, ASSIGNOR TO
THE AEOLIAN COMPANY.

TALKING-MACHINE.

1,240,038.

Specification of Letters Patent. Patented Sept. 11, 1917.

Application filed December 31, 1912. Serial No. 739,521.

To all whom it may concern:

Be it known that I, FREDERICK JAMES EMPSON, a subject of the King of Great Britain, residing at Sydney, New South Wales, Australia, have invented new and useful Improvements in Talking-Machines, of which the following is a specification.

This invention relates to improvements in talking machines and has been devised 10 with the object of improving and controlling the reproduction of the sound waves.

The said invention consists in the combination with a flexible throat or tube (for example of rubber) situated at the junction 15 of the tone-arm and horn, of a valve or plug to control the sound waves passing through said throat or tube and prior to reaching the horn, and means for operating said plug or valve from the exterior of the machine so that the operator during the rendering of a piece by the instrument may have 20 complete control over the sound waves and be thus enabled to impart to the sound waves desirable light and shade or expression and thus control the sound in a much more 25 effective manner than has been heretofore possible.

The plug or valve is preferably hemispherical and capable of being raised or 30 lowered in the throat passage or to or from the end of its smaller aperture. One mode of raising and lowering the plug is by means of a milled head or thumb nut outside the tone arm on which head is a spindle carrying 35 a light wheel or a section of one immediately over the center of the throat. The wheel or sectional wheel has attached thereto a fine silk or other suitable flexible connection to the other end of which is secured 40 the plug. Rotation of the milled head in one direction causes the wheel or sectional wheel to revolve carrying the thread and consequently raising the position of the plug in the throat while rotation in the opposite 45 direction causes the plug to descend, the passage for the sound waves being widened or contracted accordingly. A suitable spring on the spindle retains it and therefore the plug in the position desired. Another 50 mode of raising and lowering the plug or valve is by means of a Bowden wire mechanism as will be hereinafter described.

In the accompanying drawings:

Figure 1 is a general perspective view.

Fig. 2 an enlarged detailed perspective 55 view, and

Fig. 3 a sectional elevation illustrating the invention.

Figs. 4 and 5 are respectively a perspective and a sectional elevation illustrating a 60 slight modification, and

Fig. 6 illustrates a modified method of raising and lowering the plug or valve.

The same numerals indicate the same or 65 corresponding parts.

6 is the record and 7 the tone arm carrying the usual reproducing needle. 8 is the flexible throat having the flange 9, flared mouth 10, and restricted aperture 11. 12 is a milled head on a spindle 13 on which is a sectional wheel or the like 14. To said wheel is attached one end of a thread 15 at the lower end of which is a plug or valve 16. The spindle 13 is furnished with a spring 17 which while allowing of the free adjustment 70 of the spindle by the operator will retain the spindle, and the plug in any position in which it is left by the operator. 18 is an adjusting screw. The plug is preferably rounded off on one side as illustrated. 19 75 represents an indicator and 20 a pointer to show the position of the plug in the throat.

By rotating the milled head 12 it is evident that the plug 16 may be raised or lowered in the throat 8 to control the volume 80 of sound passing therethrough.

In the modification illustrated in Figs. 4 and 5 the plug 16 is caused to be raised toward or lowered from the throat aperture.

Referring to Fig. 6 which illustrates a 90 Bowden wire mechanism for actuating the plug or valve, the end of the flexible casing 21 of the Bowden wire mechanism is supported by a U-shaped frame 22 which has a ring 23 adapted to be held in place by the 95 tone-arm 7. The wire 24, on one end of which is mounted the valve 16, is controlled by a spring 25 within the casing 21, the said spring being arranged to force the wire longitudinally within the casing in a direction indicated by the arrow, thereby holding the valve normally open. The outer end of the wire is provided with a thumb piece 26 and it will be seen that with a wire of suitable length the operator can sit with the 100 audience in front of the machine and at the same time control the valve by pressing or releasing the thumb piece.

If desired means may be provided for locking the wire so that the valve may be retained in the closed or one or more intermediate open positions; such means may 5 conveniently comprise a pin 27 projecting from the wire 24 and adapted to slide in a slot 28 in the side of the casing 21. The slot 28 is provided with notches 29, and it will be seen that if the thumb piece is pressed so 10 as to bring the pin 27 opposite one of the notches and then turned so that the pin engages therewith the wire will be retained against the action of its spring.

The preferred form of the device is the 15 convex valve coöperating with the delivery end of the throat, the effect being that the sound-waves, in striking against the valve, are not baffled or reflected back into the throat to interfere with the succeeding 20 waves, but are merely deflected through the adjustable annular space between the valve and the lip of the throat, whence they pass freely into the surrounding space and out by way of the horn.

25 The valve of my sound controlling device, coöperating, as it does, with a port having a thin, elastic periphery, can be closed with a variety of degrees of tightness. This, by giving corresponding gradations 30 to the tone, tends to prevent the opening and closing of the valve from being abruptly noticeable to the listener. Further, because the port is so delicately elastic, it does not grip the valve. This is advanta- 35 geous because if the valve be forcibly gripped by its port, it tends to pop out suddenly when trying to withdraw it, and will produce a sudden, abrupt effect in spite of the fact that the intention may have been 40 to withdraw it gradually to produce a smooth crescendo.

What I claim is:

1. In a sound controlling device, the combination with a sound conduit of a plug 45 valve coöperating with a ported member whose port has a thin rubber lip.

2. In a sound controlling device, the combination with a sound conduit of a plug valve coöperating with a ported member 50 whose port has a thin yielding periphery.

3. In a sound controlling device, the combination with a sound-conduit of a valve coöperating with a ported member whose port has a thin rubber lip.

55 4. In a sound controlling device, the combination with a sound-conduit of a valve coöperating with a ported member whose port has a thin yielding periphery.

5. In a sound controlling device, the combination with a tone-arm and horn of a valve movable into and away from a ported member whose port has a thin yielding periphery, said ported member being in the 60 form of a tubular throat arranged to project the sound from the tone arm into the

horn without having its sides at said port in contact with the sides of the horn.

6. In a sound controlling device, the combination of a coöperating throat and taper plug valve opposed to the sound-waves, the 70 initial contact between said throat and valve being on a thin elastic periphery which permits the valve to be seated lightly, and after that with gradually increasing degrees of tightness to give a correspondingly gradual modulation to the sound as distinguished from an abrupt open and shut effect.

7. In a sound controlling device, the combination with a tone-arm and horn of a 80 valve movable into and away from a ported member whose port has a thin yielding lip, said ported member being in the form of a tubular throat arranged to project the sound from the tone arm into the horn and which has a reduced cross-section at its de- 85 livery end.

8. In a sound controlling device, the combination with a sound conduit of telescoping valve parts which contact with each other on a thin yielding periphery.

9. In a sound controlling device, the combination with a sound conduit of coöperating valve parts, one of which has a thin yielding portion which initially contacts 90 with the other valve parts.

10. In a sound-controlling device, the combination with a sound-conduit, of a throat mounted within said conduit so that the sound will pass therethrough and a plug valve in the conduit outside the throat co- 100 operating axially and internally with the mouth of the throat.

11. In a sound-controlling device, the combination with a sound-conduit, of a throat mounted within said conduit so that the 105 sound will pass therethrough and a plug valve in the conduit outside the throat co-operating axially and internally with the mouth of the throat, said mouth being elastic with a thin lip.

12. In a sound-controlling device, the combination with a sound-conduit, of a throat mounted within said conduit so that the sound will pass therethrough and a plug valve in the conduit outside the throat co- 115 operating axially and internally with the mouth of the throat, said mouth being elastic with a thin lip and the coöperating face of the plug valve being tapered.

13. In a talking machine the combination of a tone-arm, a flexible tube situated at the larger end of the tone-arm, a valve to control the sound waves passing through said tube, a spindle, a wheel mounted thereon, a flexible connection connecting the 125 said wheel and the said valve, and means for externally operating the spindle for the purpose set forth.

14. In a talking machine the combination of a tone-arm, a flexible tube situated at the 130

larger end of the tone-arm, and having a flared mouth at one end and a restricted aperture at the other end, a valve co-operating with the lower edge of the restricted aperture of the said flexible tube to control the sound waves passing therethrough, a spindle, a wheel mounted thereon, a flexible connection connecting the said wheel and

the said valve, and means for externally operating the spindle for the purpose set forth.

Correction in Letters Patent No. 1,240,038.

It is hereby certified that in Letters Patent No. 1,240,038, granted September 11, 1917, upon the application of Frederick J. Empson, of Sydney, New South Wales, Australia, for an improvement in "Talking-Machines," an error appears in the printed specification requiring correction as follows: Page 2, line 95, claim 9, for the word "parts" read *part*; and that the said Letters Patent should be read with this correction therein that the same may conform to the record of the case in the Patent Office.

Signed and sealed this 12th day of February, A. D., 1918.

[SEAL.]

J. T. NEWTON,

Commissioner of Patents.
